UNITED STATES PATENT OFFICE.

ISAAC L. KING, OF PAVIA, PENNSYLVANIA.

REGISTRY PACKAGE-ENVELOP.

No. 863,724.

Specification of Letters Patent.

Patented Aug. 20, 1907.

Application filed July 20, 1906. Serial No. 327,071.

To all whom it may concern:

Be it known that I, ISAAC L. KING, a citizen of the United States, residing at Pavia, in the county of Bedford and State of Pennsylvania, have invented certain new and useful Improvements in Registry Package-Envelops; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in registry envelopes for use in forwarding registered matter, through the mails, and in the provision of means for carrying a registry card in a receptacle forming a part of the envelop.

The invention comprises essentially a peculiar construction of envelop, the blank for which is so constructed that when folded, it will form, beside the usual inclosure for registered matter, a pocket formed by the flaps of the blank and in which the receipt card may be placed.

The invention consists further in various details of construction and arrangements of parts which will be hereinafter fully described and then specifically defined in the appended claims.

I illustrate my invention in the accompanying drawings, in which:—

30 Figure 1 is a view showing the blank, the address surface being upon the reverse side thereof. Fig. 2 is a rear elevation of the envelop with the flaps folded. Fig. 3 is a rear elevation with part of the flaps folded, and Fig. 4 is a rear elevation of the envelop showing 35 the top and one of the end flaps unfolded and also two of the tabs.

Reference now being had to the details of the drawings by letter, A designates a blank having the top flap B, bottom flap C and end flaps D and F. The end flap F forming the pocket is first folded over the face of the blank and afterward the bottom flap C is folded over upon the outer face of the pocket forming flap F, and a tongue C' which is cut from the bottom flap C is folded over the address face of the blank to which it 40 is held by any adhesive material, thus securely holding the bottom flap. The end flap D is provided with an elongated slit D' which is adapted to receive a flap C'

forming a part of the bottom flap C, and a slit C⁵ formed in the bottom flap C enters the slit D' when folded, thereby leaving the flap C⁴ outside of the end flap D. 50 Tongues C⁶ are cut from the bottom flap C and are adapted to fold over the outer face of the end flap D to which they are held by a suitable adhesive material. Projections D³ and D⁴ upon the end flap D are adapted one to be held over the edge of the bottom flap C and 55 the other about the end of the envelop and fastened to the rear face thereof. The projection D⁴ has a slit d therein to receive the flap C⁷ which is designed to be folded in between the pocket forming flap F and the bottom flap C, in the manner shown in Fig. 1 of the 60 drawings. The flap D has a slot d' formed therein to receive the tongue formed at the end of the flap C.

It will thus be noted from the foregoing, when taken in connection with the drawings, that a pocket is formed intermediate the flaps D and F for the reception of a card, the ends of the flap D being held by the tips D³ and D⁴ being bent about the end of the envelop, while the flap C⁷, which forms a closure for one end of the card receiving pocket, is held by its end being passed through the slit d' and the bottom of the card 70 receiving pocket being formed by the flaps C⁶, which, when the envelop is closed, are bent in the manner shown in Fig. 1 of the drawings and held in place by adhesive material. The various flaps being secured together in the manner shown and described, the top 75 flap B is fastened down, thereby securely holding any inclosure within the pocket.

What I claim is:—

A registry package envelop made of a single blank of material having a pocket forming flap F, end flap D, 80 bottom flap C and top flap B, said flap F adapted to fold over a central portion of the blank, the bottom flap C provided with a tongue struck up therefrom and designed to engage over the end of the envelop and fastened to the address surface thereof, said bottom flap C having a 85 slit C⁵ and a tongue or flap C⁴ adapted to extend through a slit D' formed in the end flap D, the contracted portions at the end of the flap D designed to engage over the end of the envelop, one of said contracted ends having a slit d for the reception of the tongue at the end of 90 the bottom flap C, as set forth.

In testimony whereof I hereunto affix my signature in the presence of two witnesses.

ISAAC L. KING.
